Primary Examiner — Jack Reickel*Assistant Examiner* — Bobby W Jones, II(74) *Attorney, Agent, or Firm* — Ziegler IP Law Group LLC.(57) **CLAIM**

The ornamental design for a holder for a water filter, as shown and described.

DESCRIPTION

FIG. 1 is a top perspective view of a holder for a water filter incorporating the new design;

FIG. 2 is a side view thereof;

FIG. 3 is a front view thereof;

FIG. 4 is a bottom view thereof;

FIG. 5 is a top view thereof; and,

FIG. 6 is a bottom perspective view thereof.

The broken line showing of a holder for a water filter is included for purpose of illustrating portions of the article and forms no part of the claimed design.
